Specification of Letters Patent.

Patented Oct. 19, 1915.

Application filed April 16, 1913. Serial No. 761,587.

To all whom it may concern:

Be it known that we, GEORGE M. MAYER and FRANK T. FOWLER, citizens of the United States, both residing at Chicago, in the county of Cook and State of Illinois, have invented certain new and useful Improvements in Resuscitating Appliances, of which the following is a specification.

The present invention relates to a new and improved construction of mechanism or device for resuscitating people or animals by the introduction of fresh air, oxygen, or mixtures of these gases or other gases into the lungs of the patient, and the withdrawal 15 of the used gases from the lungs at regular intervals.

The invention relates more particularly to that class of such mechanisms in which the flow of gases to and from the lungs is produced by some power or force other than the initial compression of the gases themselves. That is to say, the invention relates particularly to that class of mechanism in which the operation of the device 25 is brought about by some external agency, such as an operator or a specially driven motor.

While the features of the present invention are applicable to use in mechanisms for resuscitating any species of lung-animal, still they are of peculiar applicability to the resuscitation of human beings, and therefore we shall describe the mechanism as applied particularly to this service. It will be 35 understood, however, that in so doing, we in nowise limit ourselves to the use of the mechanism for this particular purpose, except as called for in the claims, but that we contemplate the use of the features of the invention in any manner desired.

The lungs, being a very delicate and frail structure, are liable to injury by subjection either to abnormal pressures or vacuums. For these reasons, any mechanism for forcing air or oxygen into the lungs and for subsequently sucking it from the lungs should be so constructed as to minimize or completely obviate the possibility of creating abnormal pressures or vacuums within 45 the lungs. The mechanism or device for this purpose should be so sensitive and should be so associated with the other mechanisms that even in the hurry and confusion likely to exist during the carrying on of the resuscitating operation, there will be no possi-

bility of injuring the lungs of the patient. Otherwise permanent damage or injury may result, such as would make it impossible to revive the patient under any circumstances. For this purpose, one feature of our invention 60 contemplates the association or combination of suitably constructed safety devices with the pressure and suction mechanism, so as to limit the pressure at which the gas may be delivered to the lungs and the 65 vacuum under which it may be removed therefrom. The gas capacity of the lungs is largely dependent upon the age and size of the patient, and, of course, the volume of gas which will be drawn in and exhaled by 70 the lungs at each breath is largely dependent upon the normal capacity of the lungs. Inasmuch as a mechanism which is intended to induce artificial respiration should cause 75 a lung movement as nearly normal as possible, it follows that the volume of gases introduced into and withdrawn from the lungs at each movement of the mechanism should correspond as nearly as possible to the normal capacity of the lungs.

Therefore, another feature of our invention relates to the provision of devices or arrangements whereby the volume of gases which will be handled at each operation of the mechanism will correspond as nearly as possible to the natural volume. This feature 85 contemplates the use of devices or arrangements whereby the capacity of the mechanism can be adjusted from time to time.

While it is a general proposition that an excessive pressure or vacuum will not be created until an excessive amount of gas has been introduced into or withdrawn from the lungs, still it is not always possible to estimate accurately the exact capacity of the lungs, and, therefore, it might be found, even after the mechanism had been adjusted to give what was supposed to be the correct volume of gas movement, when the operation was commenced, that the lungs were of abnormal size. Therefore, we have combined together the mechanisms for limiting the degrees of pressure or vacuum with the mechanisms for controlling the volume of gas, so that, taken together, they will constitute an efficient and complete safeguard for 95 the lungs.

Sometimes it is desired to reinforce the resuscitating action by the use of a certain percentage or proportion of oxygen in the 100 105 110

gases. For example, in the case of asphyxiation, it might be desired to use a large percentage of oxygen, while in another case, ordinary air might be satisfactory.

5 Therefore, another feature of the invention relates to the provision of a valve mechanism or the like whereby the ratio or proportion between oxygen and air may be controlled within wide limits, and whereby 10 the proportion which will be introduced at any instant can be estimated by examination of a scale or indicator.

Other objects and uses will appear from 15 a detailed description of the invention, which consists in the features of construction and combinations of parts hereinafter described and claimed.

In the drawings: Figure 1 shows a front elevation of the completed mechanism, with 20 the pistons in lowered position; Fig. 2 shows a side elevation corresponding to that of Fig. 1; Fig. 3 is a section taken on line 3—3 of Fig. 1, looking in the direction of the arrows; Fig. 4 is a section taken on line 4—4 25 of Fig. 3, looking in the direction of the arrows; Fig. 5 is a section taken on line 5—5 of Fig. 6, looking in the direction of the arrows; Fig. 6 is an enlarged section taken on line 6—6 of Fig. 2, looking in the 30 direction of the arrows; Fig. 7 is an enlarged section through the discharge check-valve, and taken on line 7—7 of Fig. 6, looking in the direction of the arrows; Fig. 8 is a cross section through a diaphragm 35 valve, for limiting the amount of suction which may be created; Fig. 9 is a cross section through a diaphragm valve, for limiting the amount of pressure which may be created; Fig. 10 is a vertical section through 40 one of the cylinders of the mechanism, and shows particularly the construction whereby the volume of gas handled at each operation of the device may be controlled; Fig. 45 11 is a detail section through the gas mixing valve, and taken on line 11—11 of Fig. 6, looking in the direction of the arrows; Fig. 12 is a detail of the gas passages for the mixing valve, and is a section taken on line 12—12 of Fig. 5, looking in the direction 50 of the arrows; and Fig. 13 is a detail section through the check-valve, through which the gas is delivered from the pressure cylinder, and is a section taken on line 13—13 of Fig. 6, looking in the direction 55 of the arrows.

We have shown the features of our invention as applied to a construction of mechanism which makes use of two separate cylinders with their associated pistons, one for 60 delivering the fresh gas to the lungs, and the other for withdrawing the used gas therefrom. These are the cylinders 15 and 16 respectively. Each cylinder constitutes an upright metal tubing having its upper end 65 seated and centered within a cap 17, and its

lower end within a base 18. The base is provided with a pair of side legs 19 and 20, which are spaced apart the proper distance to accommodate the foot of the operator, and are connected together by a base plate 70 21. By means of this construction, a clear space is provided between the legs, so that the operator may place his foot on the base plate to steady the mechanism during its use. A number of rods or the like 22 are 75 extended between the ears of the cap and the base, which rods serve to draw the base and cap securely against the ends of the cylinder tubes and hold the mechanism rigidly assembled. The cap and base serve the further functions of accurately spacing the cylinder tubes and of keeping them in perfect parallelism, so that a more accurate and smooth operation may be obtained.

Within the cylinders are mounted pistons 80 23 and 24 respectively, which pistons are preferably provided with upper and lower packing rings 25 and 26. Tubular piston rods 27 and 28 are connected to the pistons 23 and 24 respectively, said piston rods extending up through bearings 29 and 30 of the cap. These bearings are preferably lined by brass sleeves 31, so as to produce a better wearing mechanism. An operating handle 32 is connected to the upper ends of 90 the piston rods, by means of the pins 33, and the upper ends of the piston rods are closed by means of plugs 34.

With the mechanism as thus far described, the pistons can be forced up and down in 100 unison by the raising and lowering of the handle 32, while the device as a whole is held rigidly in position by means of the foot plate 21. In the arrangement illustrated, each piston is of the so-called single 105 acting type, that is, all of its work is performed on one stroke. Inasmuch as the upper portions of the cylinders are closed, means must be provided for permitting a free flow of air into and out from such portions of the cylinders. It is desired, however, to provide a construction whereby dust may be effectively excluded from the cylinders when the same are not in operation. In order to permit the air to flow into and 110 out from the upper portions of the cylinders, we make use of hollow piston tubes. For this purpose, each of said tubes is provided with a perforation 35 in its lower portion, and a perforation 36 is provided in its 115 upper portion. When the pistons stand in their lowermost positions, the upper perforations stand within their corresponding sleeves 31, thereby completely closing the upper portion of the cylinders. As soon as the upstroke commences, however, the perforations 36 move out from the sleeves 31, so that the air may flow freely into and out 120 of the cylinders by way of the perforations 35 and 36 and the hollow piston rods. It 125 130

will be understood, however, that the lower ends of the piston rods are completely closed, so that the spaces beneath the pistons will properly perform their functions of compressing and rarifying the gases.

5 It was previously stated that in the construction illustrated, one of the cylinders performs the function of forcing the gas into the lungs, while the other withdraws the gas from the lungs. In practice, it is customary to secure a face mask or the like over the mouth and nose of the patient, and the present mechanism is provided with connections for a tube 37, through which 10 the fresh gases are forced to the face mask, and for a tube 38, through which the used gases are withdrawn from the face mask. Between the connection 37 and the compression cylinder there is placed a valve 39, whose function it is to limit or control the pressure which may exist in the delivery tube 37; and between the suction tube 38 and the suction cylinder there is provided a valve 40, whose function it is to limit the 15 amount of suction that may exist in the tube 38. Valves and passages must be provided for properly directing the gases to and from the valves 39 and 40.

20 The compression cylinder is adapted to deliver either air or oxygen or mixtures of the same according to requirements. For this purpose, there is provided a mixing valve 41, which is mounted in an extension of the base and is provided with a plug 42 which can be turned into the desired position by a milled finger piece 43. A passage 44 has its inner end terminating at the plug, and its outer end terminating in a nipple 45, to which may be connected a tube 46 leading 25 from an oxygen generator. An air inlet opening 47 communicates with the plug, and a delivery passage 48 places the plug in communication with the lower end of the compression cylinder 15. As shown particularly in Fig. 12, the plug is provided with a cut-away portion 49, so that communication may be established between the passage 48 and the air inlet, or between the passage 48 and the oxygen passage, or between 30 the passage 48 and both the air inlet and oxygen passage simultaneously. When the latter condition exists, a mixture of air and oxygen will be handled by the compression cylinder. Manifestly, the proportion of air to oxygen will depend upon the exact 35 position of the plug, and for the purpose of giving an indication as to what the proportion is at any instant, we have provided a flange 50 on the plug, which flange has an indicating arrow or the like 51, which travels over a scale 52 suitably formed or stamped on the base. This scale may be graduated in any suitable manner to indicate the proportions of the mixture. We prefer to mount the plug in vertical posi-

tion, as illustrated, so that the scale may lie on the upper surface of the base, where it can be easily read by the operator as he manipulates the apparatus.

30 A delivery passage 53 leads from the lower end of the compression cylinder to an up-standing tube 54, which in turn leads directly to the valve 39. In order to direct the flow of gases through the compression cylinder, we have provided a suction valve 54^a at 35 the inner end of the inlet passage 48, and a discharge valve 55 at the outer end of the discharge passage 53. These valves are preferably ball check-valves, although, of course, any desired construction may be used. In 30 the particular arrangement illustrated, the inlet valve has a ball 56, seating in an enlargement at the end of the passage 48 and held in place by means of a perforated nipple 57, which screws directly into the base 35 above the ball and has the notch 57^a in its lower surface to provide communication between the passage 48 and the cylinder even when the ball is drawn up against the lower edge of the nipple. In like manner, the discharge valve 55 has a ball 58, seating in a pocket at the end of the passage 53 and held in place by the lower end of the up-standing tube 54, which tube threads into the base, as shown particularly in Fig. 13. As 40 the gases return from the lungs, through the valve 40, they pass directly to a passage 59 which leads into the lower end of the suction cylinder 16 and has a check-valve 60 at its inner end. This check-valve is similar in 45 construction to the valve 54^a. The gases are discharged from the cylinder 16 down through the check-valve 61, which is illustrated in detail in Fig. 7. It comprises a casing 62, having a U-shaped passage 63, one 50 of the arms of which carries the check ball 64, and the other arm of which connects to the lower end of the cylinder. The ball may be held in place in any suitable manner as 55 by means of a transversely extending wire 65. In order to provide as large a clear space as possible between the legs 19 and 20, the check valve 61 should seat close up 60 against the leg 20. For this reason there is not sufficient clearance to allow said check-valve to be rotated for the purpose of screwing it into place. We have, therefore, provided a nipple 66 threaded on its interior to receive one arm of the valve 62, and threaded on its exterior to screw into the base of 65 70 the machine.

75 The valves 39 and 40 are shown in detail in section in Figs. 8 and 9. Said valves are of diaphragm construction and are subjected to the influence of pressure and suction respectively, and may be adjusted to limit the pressure of delivery of gas to the lungs and the suction under which the gas is removed. The valve 39 has the diaphragm 67 dividing its interior into the spaces 80 85

and 69. The space 68 communicates with the atmosphere through the medium of a perforation 70, while the space 69 communicates with the pressure opening 71 which connects to the end of the upstanding tube 54. This space likewise connects to the delivery tube 37. A valve 72 is connected to the diaphragm and is adapted to close against a seat 73, when the diaphragm is forced back against the tension of a spring 74, by reason of the existence of an excessive pressure in the space 69. The outer end of said spring seats within a threaded plug 75, which can be adjusted back and forth in order to adjust the amount of compression in the spring for the purpose of regulating the mechanism. A cap 76 serves to protect the exposed end of the plug 75 and to give a finished appearance to the mechanism.

The valve 40 is similar in construction to the valve 39, but, of course, the valve 40 is adapted to close under suction instead of under pressure. For this purpose the diaphragm is connected to a threaded pin 77, upon which is threaded a plug 78 and contacting therewith is the compression spring 79. The inner end of this spring seats directly against a bridge 80, so that the diaphragm is normally thrown over into the position illustrated in Fig. 8. By adjusting the plug 78 back and forth on the pin, the amount of compression in the spring can be adjusted according to the suction at which it is desired that the valve shall close against the seat 78a.

In the construction illustrated, we regulate or determine the volume of gas to be handled at each operation of the mechanism, by regulating or determining the stroke of the pistons. For this purpose, we have provided means for limiting said stroke and for adjusting its amount according to requirements. On the cap 17, there is mounted a disk 81 which is held in place and is free to rotate within an encircling ring 82. This disk carries a casing 83 within which works a finger piece 84, best shown in Fig. 10, and which is normally forced inward by means of a spring 85. The inner end of the finger piece carries a wedge block 86 having its inner face beveled upward, and the outer end of the finger piece carries a knob or the like 87. Throughout the length of the piston rod 27, a number of notches 88 are provided, which are of a size to accommodate the block 86, but are spaced at various positions of angularity around the piston rod. The piston rod is secured to the handle 32, so that it cannot rotate, and therefore each one of the notches 88 travels up and down in a vertical line. The sleeve 30 which supports the upper end of the piston rod 27 is provided with notches 89 corresponding in number and angular position to the notches 88, and permitting the block 86 of the finger piece

to rest or seat against the piston rod as the same travels up and down. By rotating the disk 81 into any given position, so as to allow the block 86 to extend through the corresponding notch 89, said block will stand in position to enter the corresponding notch 88 when the piston rod has traveled up the necessary distance, thus obstructing the piston rod in its travel and preventing a further upward movement. However, the piston rod will be free to move down again by reason of the beveled face on the end of the block 86.

Inasmuch as the various notches 88 are at different positions of elevation on the piston rod, it follows that the length of stroke can be adjusted by throwing the finger piece into position to engage the desired notch. We prefer to place markings in a conspicuous place, so that the exact position of the finger piece can be predetermined. For this purpose, we have placed said markings on the upper surface of the ring 82, as shown particularly in Fig. 3, and have placed an arrow 90 on the disk 81, which arrow will point to the corresponding markings. As a simple means of division, we have illustrated the words "Infants," "5 years," "13 years," and "Adults," inasmuch as these form convenient lines of division between the different piston strokes desired. Of course, any other suitable divisions might be used, and the divisions might be of greater or less number, as desired.

In order to facilitate carrying the mechanism from place to place, we have provided means for locking the cap to the handle 32, which means we have illustrated in Fig. 4. It comprises a piston plug 91 mounted within the bearings 29 and normally forced inward by means of a spring 92. Said piston plug carries a finger piece 93, which works within a slot 94 of an encircling casing 95, so that, when it is desired to unlock the device, the piston plug can be pulled out by means of the finger piece to disengage the latter from the slot, and then the finger piece can be locked in such outer position by rotation.

In the construction illustrated, we have placed the diaphragm valves in vertical alignment and directly in front of the two cylinders. By so doing, the parts are brought within a minimum space, so that the apparatus can be packed and handled most conveniently. Furthermore, by mounting the disk 81 on the cap 17, where it can be readily observed; and by placing the scale 52 on the upper face of the base, we have brought all of the indicating devices into positions where they can be most readily observed by the operator as he manipulates the mechanism. By providing a lock between the handle 32 and the cap 17, we have supplied a construction of mechanism

which can be readily carried about, and whereby any free movement of the pistons is obviated when the apparatus is not in use.

5 While we have herein shown and described a mechanism by means of which the volume of gas handled at each stroke can be controlled, and also a mechanism whereby excessive pressures and vacuums can be prevented, still there might arise occasions when either one or both of these mechanisms might be dispensed with, as, for example, when the capacity of the lungs was definitely known, or when the operator 10 might be willing to rely entirely upon the diaphragm valves for preventing the excessive pressures and vacuums. In other words, while there may be times when it is desirable to use both of these mechanisms, 15 still under some circumstances either one or the other may be dispensed with.

Inasmuch as the rate of respiration of infants and children is different from that of adults, and in fact varies largely according 20 to the age of the infant or child, it is desirable to have an indication as to the appropriate number of strokes per minute for the particular patient under treatment. For this purpose we take advantage of the presence 25 of the ring 82 on which the age markings are placed, and we place markings on said ring adjacent to the age markings and corresponding to the number of strokes or respirations per minute which should be 30 executed for the particular age in question. For example, adjacent to the word "Infants" we place the marking 50, which is approximately 35 the number of respirations per minute which should be executed when treating 40 infants.

It is sometimes unnecessary to actually withdraw the gases from the lungs by a vacuum inasmuch as there are times when the natural contraction of the muscles and 45 diaphragm of the patient will serve to expel the gas from the lungs, at least to some extent, so that it becomes only necessary to force the gas into the lungs in the first place. Therefore, we have provided means whereby 50 the suction cylinder can be thrown out of commission leaving only the compression cylinder ready to deliver the gas to the lungs, after which it will be forced out by the natural contraction above mentioned. In the particular 55 arrangement illustrated this means comprises a plug valve 96 placed at a convenient point between the face mask and the suction cylinder, and, as illustrated, preferably being mounted in the diaphragm valve 40. This 60 plug has its side wall cut away in such a manner that when turned in one position the suction diaphragm valve 40 and the suction tube 38 can be placed in communication with the atmosphere through the opening 97, while when the plug is turned into an-

other portion the suction tube 38 will be placed directly in communication with the valve 40, the opening 97 being closed at such times.

It was previously shown that the mixing valve 41 can have its plug 42 turned into such position as to place the delivery passage 48 into communication with the air inlet opening 47 and the oxygen passage 44. With the mixing valve plug turned into this position oxygen and air will be drawn into the compression cylinder on the up-stroke of the piston thereof. However, means must be provided for preventing the oxygen coming in from the tube 46 under a slight pressure from passing directly across to the air inlet opening 47, and thus escaping when the piston of the compression cylinder is on its down-stroke. For this purpose we have provided a ball check valve 85 98 which permits air to be drawn in from the air inlet, but prevents a back flow of oxygen from the oxygen generator.

We do not limit ourselves to the construction shown and described in the specification, except as called for in the claims, but we contemplate within the scope of our invention any equivalent mechanisms operating in substantially the same way to produce substantially the same results.

We claim:

1. In a device of the class described the combination with an inspirating cylinder, of a reciprocating piston mounted therein adapted to deliver portions of gas from the cylinder under pressure, adjustable means for positively arresting the movement of the piston in one direction for the purpose of varying the volume of gas to be delivered by the piston from the cylinder, and an indicator in association with said adjustable means for indicating a suitable frequency of strokes corresponding to said adjustment.

2. In a device of the class described the combination with an inspirating cylinder, 110 of a reciprocating piston mounted therein and adapted to deliver portions of gas from the cylinder under pressure, adjustable means for positively arresting the movement of the piston in one direction for the purpose of adjusting the volume of gas to be delivered by the piston on each stroke, a scale in conjunction with said adjustable means, markings on said scale indicating ages of patients, and markings on said scale 115 indicating appropriate frequencies of reciprocations corresponding to the several positions of the adjustable means.

3. In a device of the class described the combination with an inspirating cylinder, 125 of a reciprocating piston mounted therein and adapted to deliver said portions of gas therefrom under pressure, adjustable means for positively arresting the movements of the piston to thereby control volumes of gas 130

to be delivered from the cylinder, and means for indicating appropriate frequencies of reciprocation of the piston corresponding to the several adjustments of said means.

5. 4. In a device of the class described the combination with an inspirating cylinder, of a reciprocating piston mounted therein and adapted to deliver portions of gas therefrom under pressure, a piston rod connected to said piston for the purpose of reciprocating the same, a plurality of stops located at different longitudinal positions of said rod, said stops being placed at different angular positions on the rod, and a rotary stop member adapted to be thrown into position to be engaged by a desired one of the stops on said rod to thereby limit the reciprocation of the piston rod and piston accordingly.

5. In a device of the class described the combination, with an inspirating cylinder, of a reciprocating piston mounted therein for the purpose of delivering portions of gas from the cylinder under pressure, a piston rod connected to said piston for reciprocating the same, a plurality of stops located at different longitudinal positions on the rod corresponding to desired extents of piston reciprocation, said stops being placed at varying angular positions on the rod, a rotary member mounted in position to be engaged by a desired one of said stops, to thereby limit the reciprocations of the piston, and a scale in conjunction with said member for the purpose of indicating appropriate frequencies of reciprocation corresponding to the various positions of said member.

6. In a device of the class described the combination with an inspirating cylinder, of a reciprocating piston mounted therein for the purpose of delivering portions of gas therefrom under pressure, a piston rod connected to said piston, stops on said rod, a movable member mounted in position to be engaged by a desired one of said stops to correspondingly limit the stroke of the piston rod and piston, and a scale in conjunction with said member for the purpose of indicating appropriate frequencies of reciprocation corresponding to the several positions of said rod.

7. In a device of the class described the combination with an inspirating cylinder, of a reciprocating piston mounted therein for the purpose of delivering portions of gas therefrom under pressure, a piston rod connected to said piston for the purpose of

reciprocating the same, stops on said piston rod, a movable member mounted in position to engage a desired one of said stops, a scale 60 in conjunction with said member, indications on said scale corresponding to various ages of patients and corresponding indications on the scale for designating appropriate frequencies of piston reciprocation 65 corresponding to the several positions of said member.

8. In a device of the class described the combination with an inspirating cylinder, a reciprocating piston mounted therein and 70 adapted to deliver portions of gas therefrom under pressure, a conduit for delivering the gas from the cylinder, and a limiting valve in said conduit for the purpose of limiting the pressure at which gas may be 75 delivered from said conduit to a patient's lungs.

9. In a device of the class described the combination with an inspirating cylinder, of a reciprocating piston mounted therein 80 for the purpose of delivering portions of gas therefrom under pressure, a conduit leading from the cylinder to a mouth piece, and a limit valve interposed in said conduit for the purpose of limiting the pressure at 85 which gas will be delivered to the mouth piece, to thereby protect a patient's lungs against excessive gas pressure from the inspirating cylinder.

10. In a device of the class described the 90 combination with an inspirating cylinder and an exhaust cylinder, of reciprocating pistons mounted in both of said cylinders, the piston in the inspirating cylinder being adapted to deliver portions of gas under 95 pressure to the patient's lungs, and the piston in the exhaust cylinder being adapted to withdraw portions of gas from the patient's lungs, a mouth piece, a conduit leading from the inspirating cylinder to the mouth piece, a conduit leading from the mouth piece to the exhaust cylinder, a limit valve in the first mentioned conduit to limit the pressure at which gas may be delivered to the patient's lungs, and a limit valve in the last mentioned conduit to limit the suction at which the gas may be withdrawn from the patient's lungs.
